UNITED STATES PATENT OFFICE

FREDERIC A. DAVIDSON, OF BAYSIDE, NEW YORK, ASSIGNOR TO AMERICAN SAFETY DEVICE CO., OF NEW YORK, N. Y., A CORPORATION OF NEW YORK

SAFETY GATE FOR HOISTING INCLOSURES

Application filed May 31, 1930. Serial No. 458,594.

This invention relates to safety gates for hoistway inclosures, and has for its general object and purpose to provide a simply constructed, durable and efficient adjustable gate particularly designed for application and use in connection with temporary inclosures for material hoistways provided for the transportation of materials during the erection of a building.

10 It is a more particular object of the invention to provide an adjustable gate detachably mounted on the frame of the inclosure at one side of the floor opening of the hoistway and which when in closed position, effectually 15 prevents large, heavy objects being accidentally moved over the floor into the hoistway opening and also provides a guard rail preventing the workmen from accidentally falling into the opening, the several parts of 20 the gate being so constructed and connected with each other that the gate will be self-retained in its open position entirely at one side of the frame of the inclosure where it will not interfere with the free movements of 25 the workmen in loading materials onto the hoisting platform.

With the above and other objects in view, the invention consists in the improved safety gate for hoistway inclosures and in the form, 30 construction and relative arrangement of its several parts as will be hereinafter more fully described, illustrated in the accompanying drawings, and subsequently incorporated in the subjoined claims.

35 In the drawings, wherein I have disclosed one simple and practical embodiment of the device, and in which similar reference characters designate corresponding parts throughout the several views,—

40 Figure 1 is a front elevation, the gate being shown in full lines in its closed position and in dotted lines in its open position;

Fig. 2 is a view looking at right angles to Fig. 1, and

45 Fig. 3 is a horizontal sectional view taken on the line 3—3 of Fig. 1.

The particular construction of the hoistway inclosure is fully described and claimed in a co-pending application filed of even date herewith, now issued as Patent No.

1,799,959, on April 7, 1931. For purposes of this explanation, it will suffice to state that this inclosure includes a knock-down frame structure composed of vertical tubular members 5 which are connected and rigidly supported by transverse and longitudinally extending tubular members 6 and 7 respectively, detachably connected with the members 5 by suitable coupling devices indicated at 8. At 55 opposite sides of the hoistway opening in the floor of the building where the building materials are to be loaded onto the hoistway platform, the longitudinal connecting members 7 are provided only at the upper ends of the vertical members 5 so that the space between these vertical members at their lower ends will be unobstructed during the loading 60 of the hoistway platform. Normally, however, when materials are not being loaded on the platform, the opposite open sides of the 65 hoistway inclosure are closed by the gates which form the particular subject matter of 70 this application.

As herein shown, my improved safety gate in one practical embodiment thereof includes 75 the angular tubular member 9, one end of which is adapted to be detachably secured to one of the upright or vertical frame members 5 by the clamping device shown at 10. The other arm of this angular member 9 extends 80 inwardly from the frame member 5 and to the end thereof a tubular guard rail 11 is pivotally connected at one of its ends as shown at 12. To this frame member 5 adjacent its lower end, a removable clamping 85 device 13 is attached and carries a pivot stud 14 upon which a toe board 15 is pivotally supported at one of its ends for vertical swinging movement. To this toe board in spaced relation to its other end, the lower end 90 of a rod 16 is pivotally attached as at 17, the upper end of said rod being pivotally connected to a collar 18 secured upon the guard rail 11 in spaced relation to the free end thereof.

When the gate is in its closed position, the free end of the guard rail is supported upon an outwardly projecting arm 19 detachably mounted upon the other of the frame members 5 by the clamping device 20, the end of 95 100

said arm being provided with an upstanding pin indicated at 21 between which and the frame member 5, the end of the guard rail 11 is positioned.

From the above description, and upon reference to Fig. 1 of the drawings, it will be seen that when the gate is in its closed position, the toe board 15 extends horizontally adjacent to the floor surface across the open side of the hoistway inclosure between the lower ends of the spaced frame members 5. Thus, the possibility of bricks or other large, heavy objects being accidentally moved over the floor surface into the hoistway opening and falling upon the workmen loading materials upon the hoistway platform at one of the lower floors is obviated. The guard rail 11 extending horizontally between the member 9 and the supporting arm 19 at a point spaced vertically above the toe board 15 will effectively preclude the possibility of the workmen accidentally falling into the floor opening of the hoistway.

When materials are to be loaded upon the hoistway platform, it is only necessary to swing the guard rail 11 upwardly upon the end of the member 9. Through the rod connection 16, the toe board 15 will also be pivotally swung upwardly from its supporting pivot 14 until the parts are disposed in substantially the position shown in dotted lines in Fig. 1 where the guard rail 11 will rest against one of the transverse frame members 6. In this position, it will be noted that the pivotal connection between the end of rod 16 and collar 18 is outwardly of the pivot 12 connecting the life rail 11 with the end of member 9. Thus the toe board 15 will be held or retained in its raised position against the tendency to swing downwardly by gravity to the closed position. Therefore, it will be seen that the gate is self-retained in the open position and it is unnecessary to provide any latching or securing means therefor. In this open position of the gate, it is supported in a non-obstructing position so that it will not in any way interfere with the free movements of the workmen in loading the materials from the floor of a building onto the hoistway platform.

From the foregoing description considered in connection with the accompanying drawings, it will be seen that I have provided a simply constructed and efficiently operating safety gate which can be quickly assembled and applied to the frame structure of the hoistway inclosure during the erection of the latter. The gate being largely constructed of metal, is substantially fire-proof, and while it is comparatively light in weight it is exceedingly strong and durable in its construction.

While I have herein shown and described one simple and practical embodiment of the invention, it will nevertheless, be understood

that the same is susceptible of embodiment in various other alternative structures, and I accordingly reserve the privilege of resorting to all such legitimate changes therein as may be fairly embodied within the spirit and scope of the invention as claimed.

I claim:

1. In combination with spaced vertical supports, a gate comprising upper and lower members pivotally mounted at one of their ends upon one of said supports, an element pivotally connecting said members with each other adjacent to their other ends, means on the other of said vertical supports engaged by the latter end of said upper member in the closed position of the gate, said gate members being vertically swung upwardly to open position, and a stop fixed to said first-named support for engagement by the upper gate member and located with respect to the pivoted end of said member whereby the gate will be self-retained in its open position.

2. In a safety gate for hoistway inclosures, in combination with the spaced vertical frame members at one side of the inclosure, an upper guard rail and a lower toe board pivotally mounted at one of their ends upon one of the vertical frame members, means pivotally connecting said rail and toe board with each other adjacent to their other ends for unitary swinging movement to open and closed positions, means on the other of said vertical supports engaged by the latter end of the guard rail to support the gate in closed position, and a part fixed to the first-named vertical support engaged by said guard rail when the gate is swung to open position and located with respect to the pivoted end of said guard rail whereby said connecting means acts to automatically retain the gate in its raised open position.

3. A safety gate for hoistway inclosures, in combination with the spaced vertical frame members at one side of the inclosure, a gate comprising an upper guard rail and a lower toe board, means for detachably pivotally mounting said rail and toe board at one of their ends upon one of said vertical frame members with the pivot of said guard rail out of vertical alignment with the pivot of the toe board and spaced inwardly therefrom, means pivotally connecting the guard rail and toe board with each other for unitary swinging movement to open and closed positions, means fixed to said frame member above the gate engaged by said guard rail as the gate is moved to open position whereby said connecting means automatically acts to sustain the gate in its open position, and means secured to the other of the frame members engaged by said guard rail to support said rail and the toe board in their horizontal closed position.

4. In combination with the spaced vertical

frame members of a hoistway inclosure, a safety gate comprising an upper guard rail and a lower toe board, means for detachably pivotally mounting the toe board at one of its ends upon one of said frame members, an angular bar and means for detachably clamping said bar at one of its ends to said frame member, the other end portion of the bar extending inwardly from said frame member and being pivotally connected with one end of said guard rail, means pivotally connecting said guard rail and toe board with each other, means secured to the frame member engaged by the guard rail in the upward swinging movement of the gate to open position and located with respect to the pivoted ends of said guard rail and toe board whereby the connecting means acts to automatically retain the guard rail and toe board in open position, and means detachably mounted on the other of the frame members for supporting the gate in closed position.

In testimony that I claim the foregoing as my invention, I have signed my name hereto.

25 FREDERIC A. DAVIDSON.
